RAZOR AND BLADE CHANGER

James M. Austin, Old Westbury, N. Y.

Application May 24, 1950, Serial No. 163,909

4 Claims. (Cl. 30—40)

This invention relates to improvements in razors. It is an object of the invention to provide an improved form of razor, which is adapted to automatic blade changing.

A further object of the invention is to provide such a razor having improved mechanism for separating the blade holding elements so as to release the blade.

In my prior application, Serial No. 159,038, filed April 29, 1950, for improvements in Razors and Blade Magazines Therefor, I have disclosed a razor and automatic blade changer operable therewith, the razor being arranged for opening by means of projections on the guard which pass through apertures in the back to engage a razor support in the blade changer. The present invention makes provision for opening the razor without requiring such projections on the guard of the razor.

With the foregoing objects in mind, as well as others which will appear, the invention consists in the combinations and arrangements of parts which will now be described with reference to the accompanying drawing and then be pointed out more particularly in the appended claims.

In the drawing:

Figure 1 is a front elevation view of a razor embodying the invention in a preferred form of embodiment and showing the same in position in the razor holding means of a blade changer;

Figure 2 is a view similar to Figure 1 with the razor and magazines removed;

Figure 3 is a section on line 3—3 of Figure 2;

Figure 4 is a section on the line 4—4 of Figure 1, showing also the box of the blade changer;

Figure 5 is a side elevation of the razor.

Figure 6 is a back elevation of the razor; and

Figure 7 is an end elevation of the razor.

The razor comprises a handle 1, in which there are riveted or otherwise secured, a back 2 and a spring 3. A ferrule 4 may be provided, the parts being conveniently held together by a rivet passing through all four elements. A guard 6 is held against the back 2 by the spring 3, as indicated. The back 2 has an angularly disposed flange forming a cap 7 and the blade B is held between this cap and the guard, as indicated. The blade is held accurately in position by means of lugs 8 at the ends of the guard, and the spring 3 working against the guard and pushing the same toward the back also pushes the blade back under the cap and against the angle of the back, as shown in Figure 5. Since the blade is engaged by the lugs 8 only at its ends, which are beveled slightly as shown, practically the entire cutting edge is available for shaving. The guard is held in position on the back by projections 10 passing through apertures 11 in the back, as shown, and the back is provided with apertures 12 for accommodating projections on the blade changer, as hereinafter described.

The mechanism for accomplishing the blade change is not shown herein and may be any suitable mechanism such as is shown and described in my application above referred to. In the present application, there is

2

shown only the mechanism for holding the razor in position for a blade change. This mechanism comprises a plate 17 arranged to hold magazines 15 and 16 for new and used blades respectively, by means of projections 19 and other arrangements (only part of the plate and magazines being shown in the drawing). The plate is formed with upstanding flange like elements 20, which are bent over slightly so as to hook over the cap 7 of the razor when the razor is held upon the plate 17, and with projections 23 adapted to pass through the apertures 12 in the back of the razor for forcing the guard upwardly as shown in Figure 4. The back of the razor is held down flat against the plate 17 by a spring clip 21 which goes through opening 22 in the back of the razor and hooks over the edge of this opening. By these means, the razor is securely and firmly held in position on the plate, with predetermined relation to the magazines held thereby and the guard and back of the razor are separated so as to permit a blade change by sliding a new blade into the razor in alignment with the used blade therein so as to push the used blade into the used blade magazine.

What is claimed is:

1. The combination of a razor and a holder, the razor comprising a back, a guard and means for yieldably holding them together in blade holding relation, the back comprising a portion for overlying the blade and a supporting portion attaching the same to the handle and disposed at an angle to the first said portion, and the holder comprising a support, means for holding the supporting portion of the back of the razor down on the support and means for engaging the guard to force it away from the back and release the blade when the back is so held on the support.

2. The combination of a razor and a holder, the razor comprising a back, a guard and means for yieldably holding them together in blade holding relation, the back comprising a portion for overlying the blade and a supporting portion attaching the same to the handle and disposed at an angle to the first said portion, and the holder comprising a support, means for holding the supporting portion of the back of the razor down on the support and projections on the support for engaging the guard to force it away from the back and release the blade when the back is so held on the support.

3. The combination of a razor and a holder, the razor comprising a back having an aperture, a guard overlying the aperture, and means for yieldably holding the back and guard together in blade holding relation, and the holder comprising a support, means for holding the back of the razor down on the support and a projection positioned to pass through the aperture and engage the guard to force it away from the back and release the blade when the back is so held on the support.

4. The combination of a razor and a holder, the razor comprising a back having a pair of apertures, a guard overlying the apertures, and means for yieldably holding the back and guard together for holding a blade with the apertures equidistant from the blade and from its ends, and the holder comprising a support, means for holding the back of the razor down on the support and projections positioned to pass through the apertures and engage the guard to force it away from the back and release the blade when the back is so held on the support.
